REFRIGERATOR VENTILATOR SYSTEM

Lewis M. Mitchell, Greeley, Colo.; Wilbur A. E. Mitchell, administrator of said Lewis M. Mitchell, deceased, assignor of 46.66% to Wilbur A. E. Mitchell, Greeley, Colo., 26.67% to Paul M. Mitchell, Chicago, Ill., and 26.67% to Gerald L. J. Mitchell, Glen Ellyn, Ill.

Application November 23, 1944, Serial No. 564,882

7 Claims. (Cl. 98—51)

1

This invention relates to the problem in refrigeration of ventilation of the refrigerator unit, whether the unit be a box, cabinet, compartment or room. Food stored in conventional units becomes odorous and the air therein stale, resulting in other foods becoming tainted with unnatural flavors. Furthermore, mechanical units have been found to operate better if the air in the unit is fresh and not stagnant with food and other humid saturation causes from lack of ventilation. My invention relates also to food storage units, generally.

One of the objects of my invention is to provide a mechanical ventilating system which will operate to ventilate the unit automatically upon use of the refrigerator unit.

I provide ventilating means operable to utilize the fresh air, which enters the refrigerator unit upon use of the door to the unit, to leave the unit after the door is closed and thereby ventilate the unit.

A further object is to provide a ventilating system operable upon and after the door to the refrigerator unit has been used; and also, I provide means for predetermining the interval of time during which my ventilating system operates after the door to the unit has been closed, according to the need arising from the foods being stored in the unit.

Other and further objects and advantages of my invention will be discernible to those skilled in the art, and I am not limiting myself by the specific disclosure in this specification, but only by the spirit and scope of the specification in its entirety including the appended claims. For instance, I have illustrated my invention herein by way of disclosure of its use in connection with a household refrigerator, but, obviously, it is applicable as well to commercial refrigerators and refrigerator storage units, rooms, cabinets and counters.

Referring now to the drawings:

Figure 1 is a perspective view of a home mechanical refrigerator unit, having my ventilating means 12 partially visible at the top.

Figure 2 is a vertical sectional view of that box, with the outside door shown as partially open.

Figure 3 is an enlarged longitudinal sectional view of my one-directional connecting means 33—34, which connects my ventilating means to the door 11 and initiates the operation thereof upon opening of that door 11.

Figure 4 is an enlarged partially cross-sectional view of my adjustable pneumatic door stop means.

Referring to Figure 2 of the drawings, at the

5 top of the unit or box 10, I provide an inner inverted conical-shaped false top 15. 15 is built into the box in that shape so as to deflect warm air rising upwardly in the box into the vent outlet or means 12, at the top of the unit, through openings 16 and permit departure of that air from the unit through holes 13 above the top of the unit proper. I mount a plate 4 completely across ventilator 12, so as to protect exit holes 13 by the plate protruding outwardly over and beyond them.

10 A trap door 17, with lower protruding arm 20, is provided to close the opening 16, and operable to be opened, by being pivotally mounted at 18, as illustrated, as a ventilating door. Spring 19 is so mounted, with one end fixed to the wall of the unit, and the other end to the trap door 17, that it normally acts to hold that trap door in pivotally closed position over opening 16, as illustrated in dotted lines in Figure 2, after the main door 11 has been closed for an interval, as will be later explained.

15 To the inside wall of the unit 10, at 9 I mount on a loose pivot, one end of a conventional pneumatic door stop 31, and pivotally fasten the plunger end of that stop to the lower end 32 of tray door arm 20. Free movement of the plunger end of that vacuum door stop is to the right, as illustrated, and the resisting force thereof is when

20 that plunger is pushed to the left, as will be more fully explained, and as is well known in the art. I use 31 as a retarding means to the closing of the trap door 17 by the spring 19, after the main door 11 is closed, as will be explained. Referring to Figure 4, my pneumatic door stop 31

25 comprises a pump type tubular casing 21 open at one end, having an operable plunger 22 through that open end, and closed at the other end. Plunger 22 is suitable secured to arm 34 by any conventional means such as illustrated, and has a supporting washer and a flexible leather, or other flexible compression washer 23, snugly held as illustrated and understood in the art. Washer 23 acts as a compression seal in one direction 30 only between 22 and 21. A lubricant is applied periodically to the inner walls of the casing. Compression of air in the casing occurs, since the other end, as illustrated, is formed closed, as the plunger is operated toward that closed end. An air outlet port is provided at 24, adjacent the closed end; and a plug 25 is suitably secured, as by welding, to the exterior of the casing in alignment with port 24. Plug 25 has a longitudinal opening corresponding in size to 24, and aligned 35 with 24 throughout its length. Extending out-

wardly transversely of the plug from its central longitudinal opening are a plurality of outlet vents 26, through which vents 26 the compressed air, in compression chamber 28 end of the pneumatic stop, upon operation thereof, escapes. As elsewhere explained, arm 34 is actuated in compression direction by spring 19. Plug 25 is externally threaded to receive a threaded U-shaped seal cap 27 thereover. Cap 27 is operably adjusted on said threads to close the extended port 10 24 and also one or more or all of the vents 26, as will be understood; thereby, in direct proportion to that closing by 27, the interval of time required for the release of the compressed air in chamber 28 is controlled or adjusted. Obviously, 15 an adjustment of cap 27 on its threads, to close or open one or more of vents 26 in plug 25, regulates the interval of time it takes the tension means 19 to close the trap or vent door 17 after door 11 has been closed, as will be more fully explained, by a confining or release, respectively, of compressed air in compression chamber 28 of the pneumatic stop member 31, upon operation 20 of the plunger 22 in casing 21. Upon opening of the door 11, the arm 34 and plunger 22 are withdrawn from the compression end of casing, and in that operation air enters the compression chamber 28 through vents 26 and port 24, as will be understood. Any number and size of vents 26 may be provided; and also a plurality of ports 24 each with a plug 25, vents 26 and cap 27 may be provided, as desired or necessitated under varying conditions of use.

Also at the lower end 32, of trap door arm 20, I pivotally mount to the right the one-directional free plunger arm 34, which, with 33, comprises one-directional connection means between door 11 and arm 20, as will be explained. Arm 34 is the inner, free one-directional, loose fitting piston portion of the connecting means 33—34 between 32 and 37. Member 33 is a tubular member open at the left end where arm 34 enters it, and is closed at its right side where it is pivotally connected to the outer door 11, at 37. When door 11 is opened, and tubular sleeve 33 is pulled with it to the right, as illustrated, notch 35 of 33 engages against notch 36 of 34, and thus in that opening direction of door 11 members 33 and 34 act as a solid connecting means pulling arm 20 so as to open trap door 17, on its pivot 18, with that openings of door 11. From that construction, it will appear that when door 11 is closed sleeve 33 will slide over loose fitting arm 34 without exerting any force in that direction, or to the left as illustrated, on or through that arm 34. Thus arm 34 and tubular member 33 together comprise one-directional connecting means between arm 20 extension of the trap door portion 17 and the door 11. Thereby, when door 11 is opened trap door 17 is also opened; and when door 11 is closed nothing happens to trap door 17 as a result of that closing; as arm 34 is shorter than openings 29 of tubular member 33 and thus does not force 34 to the left.

When door 11 is closed, trap door 17 will remain open for a while, due to pneumatic door stop 31 exerting a pressure against arm 20, as arm 20 moves to the left as illustrated, under the pressure resulting from spring 19. In other words, spring 19 causes trap door 17 to close slowly against the resistance of pneumatic stop 31, after the main door 11 has been closed. That length of time that it will take for spring 19 to close trap door 17 across opening 16 can be regulated by the proportion of the tension or pull of

spring 19 over the resistance against the plunger in stop 31, and hence against arm 20. That time it will take before trap door 17 closes, after closing of door 11, can be regulated as desired—that is, predetermined—from time to time, as heretofore explained relative to my pneumatic stop 31, by an adjustment of cap 27 to open or close one or more of the outlet vents 26 and port 24 thereof, to thereby permit a quick close of trap door 17 after door 11 is closed, or to cause a delayed close thereof.

It will thus be seen, that during that interval of time, after main door 11 is closed, and while trap door 17 is closing slowly across opening 16, as just explained, that a volume of air will be forced up and out the ventilating means 12 by the air forced into the box when door 11 is closed, since trap door 17 is not yet closed. Also, during that interval after door 11 is closed and before trap door 17 is closed, the warmer air which entered before door 11 was closed will rise of its own force to the top of the box and will be deflected out through opening 16 upwardly and out holes 12. Of course, ventilation also occurs when front door 11 is held open, as during that time the trap door 17 is also thereby held open, as previously explained, thus permitting fresh air to enter the unit and rise of its own warmth and out of the unit through my vent at the top, while the heaviest saturated air naturally falls downwardly out the door 11 of the unit as that door is held open.

A refrigerator unit with my invention will always be automatically ventilated and fresh, with the result that foods will be kept longer therein and without taking on foreign food odors.

In Figure 2, I diagrammatically illustrate the conventional cooling mechanism, connections and unit, as 38, 39 and 40. When the small home box 10 of the size illustrated is in use it is generally about jammed with foods, bottles and containers, and the air therein seldom properly circulates because it becomes saturated, and yet the proper functioning of that small mechanical unit depends upon 45 circulation. In a unit having my ventilator improvement, the efficiency of such a box through better circulation obviously results.

While I have illustrated and described one embodiment of my invention, it is obvious to those skilled in the art that there are other embodiments, modifications, uses and advantages, within the spirit and scope of my invention; for instance, my ventilating means 12, trap door 17, spring 19, stop 31 and my one-directional connecting means 33—34, could be rearranged, redesigned, substituted for and eliminated in part, without changing the spirit or scope of my invention, or deviating therefrom. There might be times, for instance, when it would be desirable to 60 eliminate the spring 19 and stop 31, and, instead of the one-directional only connecting means 33—34 herein described and illustrated, to have a solid connection between 32 and 37, so that the trap door 17 would open and close simultaneously 65 with and upon the operation of the front door 11.

I therefore wish to be limited only by the spirit and scope of the appended claims.

What I claim as my invention is:

1. In a refrigerating unit, a cooling compartment having an outside main door, a vent opening in a wall of said unit, a trap door pivotally mounted across said vent opening, spring means for normally holding said trap door in closed position across said vent opening, one-direction 70 connecting means between said outside main door 75 and upon the operation of the front door 11.

and said trap door operable for opening said trap door when the main door is opened against the tension of said spring means, and pneumatic door stop means so attached to said trap door as to prevent its being closed by said spring means until the lapse of an interval after the main door is closed.

2. A refrigerator unit as claimed in claim 1, characterized by the provision of the pneumatic door stop means being adjustable for regulation of the interval between the closing of the main door and the trap door.

3. The combination, in a refrigerator unit having a main door, an operable vent door normally held closed by a tension means and adapted to be opened by and when the main door is opened, and telescoping members comprising connecting means between the two doors for opening of the vent door upon the opening of the main door, of tension means associated with the connecting means for normally holding the vent door closed and for closing the vent door after the main door has been opened and after the main door has been closed and having pneumatic door stop retarding means in association therewith for retarding the closing of the vent door once the vent door has been opened.

4. In a refrigerator unit, a cooling compartment having an outside main door, a vent opening in a wall of said unit, vent door means operably mounted across said vent, tension means for normally holding said vent door means in closed position with relation to the vent, one-directional connecting means between the outside door and the vent door means operable for opening the vent door means when the main door is opened against the tension of the tension means and further operable for permitting closing of the main door without causing a closing of the vent door, and retarding means operably connected with said vent door means for causing the vent door means to be closed slowly by the tension means after the vent door means has been opened and after the main door has been closed.

5. A refrigerator unit as claimed in claim 4, characterized by the provision of the retarding means being adjustable for regulating the interval of time it takes the tension means to close the vent door means after the main door has been closed.

6. A food storage unit comprising an entrance door, a vent door operably adapted to be nor-

mally held closed, and connecting means comprising rod means mounted in a sleeve provided with a notched means for moving the rod in one direction, said connecting means being positioned between the two doors for opening operation of the vent door by the opening of the entrance door and for operational closing of the vent door an interval of time after the entrance door has been closed, and said connecting means having tension means associated therewith for normally holding the vent door closed and for closing the vent door after it has been opened and also having retarding means associated therewith for resisting the closing of the vent door.

7. A ventilating system for a storage unit of the class described, having a main door and a vent opening therein, comprising a vent door operably mounted across said vent and normally adapted to be held closed with relation thereto, tension means for normally holding the vent door closed, and one-directional mechanical connecting means comprising telescoping members between the two doors for opening of the vent door by and upon the opening of the main door and for permitting the vent door to remain open for a period of time after the main door has been closed.
